CLAIM

The ornamental design for a mosquito lamp, as shown and described.

DESCRIPTION

FIG. 1 is a perspective view of a mosquito lamp showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear side perspective view thereof.

Any shading and cross-hatching are not features of the design but are utilized to illustrate the surface contours of the mosquito lamp design in the drawings.

The broken lines in the drawings depict portions of the mosquito lamp that form no part of the claimed design.
